UNITED STATES PATENT OFFICE.

THOMAS BEECHER, OF NEW HAVEN, CONNECTICUT, ASSIGNOR OF ONE-HALF TO JOHN A. HULL, OF SAME PLACE.

COACH-STEP.

SPECIFICATION forming part of Letters Patent No. 644,842, dated March 6, 1900.

Application filed July 20, 1899. Serial No. 724,515. (No model.)

To all whom it may concern:

Be it known that I, THOMAS BEECHER, a citizen of the United States, residing at New Haven, in the county of New Haven and State of Connecticut, have invented certain new and useful Improvements in Coach-Steps, of which the following is a specification, reference being had therein to the accompanying drawings.

10 My invention relates to improvements in coach-steps, its object being to improve the construction thereof and to facilitate and cheapen the cost of manufacture.

To this end my invention consists of the 15 coach-step having certain details of construction and combinations of parts, as will be hereinafter described, and more particularly pointed out in the claims.

Referring to the drawings, in which like 20 numerals designate like parts in the several views, Figure 1 is a view of the under side of the step, showing the fastening-cleats. Fig. 2 is a side elevation of the step. Fig. 3 is a sectional view of Fig. 1 upon line 1 1. 25 Fig. 4 is a sectional view of Fig. 1 upon line 2 2. Fig. 5 is a view of the under side of the tread-bar frame. Fig. 6 is a fragmentary side elevation of the said tread-bar frame. Fig. 7 is a fragmentary under side view of 30 the step, showing a modification of the fastening device. Fig. 8 is a sectional view of Fig. 7 upon line 3 3. Fig. 9 is a plan view of a tread-bar frame having rubber step-pads. Fig. 10 is a transverse section of one of the 35 pads and channel-bars, taken on line A B of Fig. 9. Fig. 11 is a longitudinal section of the tread-bar frame upon line D D of Fig. 9.

The numeral 1 designates the step-frame, which is preferably made of wrought metal 40 and may be of any desired shape or size. Projecting laterally from one side of the said frame is the integral shank 2, which is designed to be forged to the step-bracket, that is fastened to the body of the coach or carriage. The top side of the shank is substantially flush with the top of the tread-bar frame, and the bottom portion extends under the frame (see Figs. 1 and 2) to the edge 45 of the aperture therethrough and materially increases the strength of the step.

The tread-bar frame 3 is ordinarily made

of cast metal and comprises a series of tread-bars 3^a, integral with the body portion 3^b, which is of substantially the same contour and size as the aperture in the step-frame, a 55 flange portion 3^c projecting laterally from the top side and a plurality of fastening-cleats 4 projecting downward from the bottom thereof.

In manufacturing these steps the step-frame 1 is shrunk upon the tread-bar frame 3, with the flange 3^c resting upon the top side of the said step-frame, and thereby uniting the said frames into a solid inseparable whole. The fastening-cleats 4 are turned over into recesses made in the bottom of the frame, 60 (see Fig. 1,) forming a bottom flange, and that edge 6 of the shank which abuts against the flange 3^c is turned over upon the top thereof, thus insuring a strong connection and a fine finish. That portion of the body 65 of the tread-bar frame which is immediately adjacent to the shank 2 is rounded to conform to the contour of said shank, and a fastening-screw 5 prevents them from becoming separated. The parts are finished by either 70 filing or polishing, leaving the upper and lower surfaces of the step smooth and flat 75 without projecting parts.

Many ways have been devised to securely fasten tread-bars in the step-frame, but all 80 have proved unsatisfactory, either because the constant jar upon the step loosens them or because the cost of manufacture is too great.

By constructing a step as herein described the tread-bars are all rigidly secured together 85 and being of cast metal can be cheaply produced. The step-frame is securely fastened to the tread-bar frame by the shrinking process, aided by the upper flange and the fastening-cleats. Instead of fastening-cleats I can 90 use screws 7, (see Figs. 7 and 8,) which are screwed into a threaded hole formed in both of the frames, the top of the screws being slightly below the surface of said frames. After the screws are inserted that portion of the 95 frames immediately surrounding the screw-holes is upset to close the open end thereof and effectually prevent the screws from becoming dislodged by jar or wear.

It is not essential that a recess should be 100 formed in the bottom of the step-frame for the reception of the cleats 4; neither is it ab-

solutely necessary to shrink the step-frame upon the tread-bar frame, as it may be rigidly secured by the aid of the flange 3° and the cleats 4.

5 In Fig. 9 I have illustrated a tread-bar frame having the usual rubber pads 8 for the tread in place of the metal bars, as above described. The pads 8, which are T shape in cross-section, are inserted in the channel-bars 10, integral 10 with the tread-bar frame, and securely fastened therein by means of screws 9, which pass through the bottom of said channel-bar into the pads. It has been customary to hold these pads in place by pressing the sides of 15 the channel-bars together, and thus pinching the pads. After much use, however, the pads become loosened and drop out, marring the beauty and usefulness of the step. By my improved means the pads are fastened se- 20 curely in place and cannot be removed except by design.

Having described my invention, what I claim as new, and desire to secure by Letters Patent, is—

25 1. In a carriage-step the combination of a tread-bar frame having an overhanging flange and fastening-cleats, of a step-frame surrounding the body portion of said tread-bar frame and shrunk thereon, whereby the said 30 frames become inseparable, substantially as described.

2. In a carriage-step the combination with a tread-bar frame having an overhanging flange upon the top side and fastening-cleats

which form a flange upon the bottom side 35 thereof, of a step-frame surrounding the body portion of said tread-bar frame, the said overhanging flange being against one side and the said fastening-cleats against the opposite side of said step-frame, all constructed and oper- 40 ating substantially as described.

3. In a carriage-step the combination with a tread-bar frame 3 having the flange 3° and fastening-cleats 4 integral therewith of a step- 45 frame 1 provided with the shank 2 substan- tially as described.

4. In a carriage-step having a plurality of channel tread-bars, the combination there- 50 with of a plurality of rubber pads which are adapted to be inserted in the said channel- bar and means, as locking-screws, for rigidly securing said pads within the said channel tread-bars, substantially as described.

5. In a carriage-step the combination with a tread-bar frame 3 having a plurality of 55 channel tread-bars 10, of a plurality of rubber pads 8 substantially T shape in cross- section, the body portion of which is adapted to be inserted in said channel-bars and lock- ing-screws, as 9, for fastening the said pads 60 within the said channel-bars, substantially as described.

In testimony whereof I affix my signature in presence of two witnesses.

THOMAS BEECHER.
